(57) **CLAIM**

The ornamental design for a facial cleansing appliance, as shown and described.

DESCRIPTION

FIG. 1 is a front perspective view of a facial cleansing appliance showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof; and,

FIG. 9 is a perspective view showing a usage state, in which a container fitted with the facial cleansing appliance is shown in broken lines forming no part of the claimed design. The broken lines depict portions of the facial cleansing appliance in which the design is embodied that form no part of the claimed design.

1 Claim, 7 Drawing Sheets
